(57) **CLAIM**

I claim the ornamental design for a litter box with pour spout and handles, as shown and described.

DESCRIPTION

FIG. 1 is a first top perspective view of a litter box with pour spout and handles showing my new design;

FIG. 2 is a second top perspective view thereof;

FIG. 3 is a bottom perspective view thereof;

FIG. 4 is a left-side elevation view thereof;

FIG. 5 is a right-side elevation view thereof;

FIG. 6 is a front elevation view thereof;

FIG. 7 is a back elevation thereof;

FIG. 8 is a top plan view thereof; and,

FIG. 9 is a bottom plan view thereof.

1 Claim, 9 Drawing Sheets
